UNITED STATES PATENT OFFICE.

ROBERT E. ADREON, OF ST. LOUIS, MISSOURI, AND CHRISTOPHER P. CASS, OF BERKELEY, CALIFORNIA, ASSIGNEES TO THE AMERICAN BRAKE COMPANY, OF ST. LOUIS, MISSOURI, A CORPORATION OF MISSOURI.

SLACK ADJUSTER.

Application filed July 19, 1922. Serial No. 575,934.

To all whom it may concern:

Be it known that we, ROBERT E. ADREON and CHRISTOPHER P. CASS, citizens of the United States, residents, respectively, of St.

5 Louis, State of Missouri, and Berkeley, in the county of Alameda and State of California, have jointly invented certain new and useful Improvements in Slack Adjusters, of which the following is a specifica-

10 tion.

This invention relates to slack adjusters employed for automatically taking up slack in the brake rigging due to the wear of the brake shoes on the wheels.

15 It has heretofore been proposed to apply a take-up cylinder to the tie rod connecting the usual brake levers and one object of our invention is to provide a construction of the above character in which the take-up cylinder is entirely supported by the tie rod, so that the operation of the slack adjuster will not be affected by movement of the car body on its supporting springs nor by the relative 20 longitudinal movement of the tie rod, due to 25 the brakes being applied.

Other objects and advantages will appear in the following more detailed description of the invention.

In the accompanying drawing; Fig. 1 is a 30 side elevation, partly in section, of a brake lever tie rod with a take-up cylinder applied thereto in accordance with our invention; Fig. 2 a section on the line 2—2 of Fig. 1; Fig. 3 a plan view, partly in section; and 35 Fig. 4 a diagrammatic view of a car brake equipment with the improved slack adjuster applied thereto.

In accordance with our invention, the take-up cylinder is made a rigid part of the 40 tie rod and for this purpose the take-up cylinder may comprise a casing 1 having opposite flange faces to one of which is applied a jaw casting 2 having the usual jaw 3 at the outer end for connection to one of the 45 brake levers. To the opposite flange face is applied a sleeve casting 4, the members 2 and 4 being secured to the casing 1 by means of bolts 5.

50 Telescoping into the sleeve casting 4 is a jaw casting 6 having a jaw at the outer end by which the same may be pivotally secured to the other brake lever. An adjusting screw 7 is secured to the jaw casting 6, as by means of a pin 8, the screw 7 having screw-threaded

engagement with a nut 9 mounted in the 55 take-up cylinder. Secured to said nut by a key pin 10 is a ratchet wheel 11 and mounted in the cylinder 1 is a piston 12 having pivotally mounted thereon a pawl 13 adapted to engage the teeth of the ratchet wheel 11. 60 Said piston carries a member 14 which extends to the opposite side of the ratchet wheel 11 and serves as an abutment for coil springs 15 and 16.

In order to prevent rotation of the piston 65 12, the member 14 may be provided with a lug 17 adapted to engage between longitudinal ribs 18 formed on the casing. The chamber 19 above the piston 12 is connected by a flexible pipe 20 to the usual port in the 70 brake cylinder so that when the stroke of the brake cylinder piston exceeds a predetermined amount, the port is uncovered, and air from the brake cylinder is supplied to the take-up piston.

75 In operation, if the brakes are applied and the wear of the brake shoes is such that the stroke of the brake cylinder piston exceeds the predetermined amount, then fluid from the brake cylinder is supplied through pipe 80 20 to piston chamber 19 and piston 12 is then moved to shift the pawl 13 so that a succeeding tooth in the ratchet wheel 11 is engaged. When the brakes are released, the exhaust of fluid from the piston chamber 19 85 permits the springs 15 and 16 to shift the piston 12 and the pawl 13, so that the ratchet wheel 11 is rotated by the pawl. The corresponding rotation of the nut 9 causes a movement to the left of the adjusting screw 90 7 thus shortening the tie rod, the screw being held against rotation by being secured to the jaw casing 6.

The tie rod is thus shortened to take up slack and when by successive adjustments, 95 the screw 7 engages the relief wedge 21, said wedge may be tapped on the under side, so as to permit the pawl 13 and piston 12 to complete their stroke.

A felt washer 22 may be placed in a 100 groove in the sleeve member 4 so as to bear against the jaw casting 6 and thus prevent the entrance of dirt, moisture and the like.

105 It will now be seen that the take-up cylinder forms a part of and is supported and prevented from rotation by the tie rod, so that no support from the car body or other outside members is required.

In Fig. 4, the slack adjuster is shown applied with the member 3 connected to brake lever 23 and the member 6 to brake lever 24, said brake levers being operatively connected to the brake cylinder 25.

Having now described our invention, what we claim as new and desire to secure by Letters Patent, is:

1. In a slack adjuster, the combination with a floating tie rod for the brake cylinder levers, of a slack take-up cylinder supported entirely by the tie rod.
2. The combination with a floating brake cylinder lever tie rod, of a fluid pressure operated slack adjuster supported entirely by said tie rod.
3. The combination with a floating brake cylinder lever tie rod, of a fluid pressure operated slack adjuster associated with and supported entirely by said tie rod.
4. The combination with a pair of tie rod members, each secured to a brake lever, of a take-up cylinder fixed to one member and a slack adjusting screw fixed to the other member.
5. The combination with a pair of tie rod members, each secured to a brake lever, of a take-up cylinder fixed to one member, a nut associated with said cylinder, and a screw fixed to the other member and having screw-threaded engagement with said nut.

6. The combination with a pair of brake levers and a tie rod member connected to each brake lever, of a take-up cylinder interposed between said brake levers and fixed to one member and a sleeve fixed to said cylinder, into which the other member is telescoped.

7. The combination with a pair of brake levers and a tie rod member connected to each brake lever, of a take-up cylinder interposed between said brake levers and fixed to one member, a sleeve fixed to said cylinder, into which the other tie rod member is telescoped, and an adjusting screw fixed to the telescoped member.

8. The combination with a pair of brake levers of a jaw casting pivotally connected to each brake lever, a take-up cylinder fixedly secured to one jaw casting, and a sleeve member fixedly secured to said cylinder and having the other jaw casting slidably mounted therein.

9. In a slack adjuster, the combination with an adjusting screw and means for moving said screw longitudinally to take-up slack, of a movable wedge shaped key engageable by said screw upon a predetermined longitudinal movement of the screw.

In testimony whereof we have hereunto set out hands.

ROBERT E. ADREON,
CHRISTOPHER P. CASS.
